CLAIM

The ornamental design for dock for mobile communication terminal, as shown and described.

DESCRIPTION

FIG. 1 is a perspective view of dock for mobile communication terminal, showing a new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is an alternate perspective view thereof, showing the dock for mobile communication terminal in an environment of use.

The broken lines shown in FIGS. 1–3 and 5–8 are included for the purpose of illustrating environmental elements only and form no part of the claimed design.
